UNITED STATES PATENT OFFICE.

CARL G. MUENCH, OF ST. PAUL, MINNESOTA.

INDENTED FIBER BOARD.

1,417,552.

Specification of Letters Patent. Patented May 30, 1922.

Application filed September 29, 1920. Serial No. 413,549.

To all whom it may concern:

Be it known that I, CARL G. MUENCH, a citizen of the United States, residing at St. Paul, in the county of Ramsey and State 5 of Minnesota, have invented certain new and useful Improvements in Indented Fiber Boards; and I do hereby declare the following to be a full, clear, and exact description of the invention, such as will enable others 10 skilled in the art to which it appertains to make and use the same.

This invention relates to indented fiber boards and has for its object to produce a board which will be more efficient in use 15 than those heretofore proposed.

With these and other objects in view, the invention consists in the novel article hereinafter disclosed and particularly pointed out in the claims.

20 Referring to the accompanying drawings forming a part of this specification in which like numerals designate like parts in all the views:—

Figure 1 is a diagrammatic sectional view 25 of a fiber board, illustrating the manner of carrying out the present process;

Fig. 2 is a fragmentary plan view of the finished board;

Fig. 3 is an end elevational view of a portion 30 of the apparatus shown in Fig. 1, and which is suitable for carrying out the present process;

Fig. 4 is a vertical sectional view taken on the line 4—4 of Fig. 3; and

35 Fig. 5 is an enlarged diagrammatic sectional view of a portion of the board shown in Figures 1 and 2, illustrating it in use.

1 indicates a fiber board which is composed 40 of a plurality of classes or sizes of felted cellulose fibers, including the sliver-like fibers 2, of from say 1/16 of an inch to 1/8 of an inch wide, and 1/2 inch or more in length; thread-like fibers 3, which may be from 1/32 to 1/64 of an inch in diameter, 45 and from 1/2 to 1 inch or more long; hair-like fibers 4, of from 1/100 to 1/200 of an inch in diameter, and from 1 to 2 inches or more long; and relatively short and very fine fibers 5, such as are ordinarily used in 50 paper making.

Boards made as above indicated are very light and porous, due to the sliver-like fibers 2; are relatively strong, due to the thorough interweaving or entangling of the 55 long thread- and hair-like fibers 3 and 4; and have a comparatively smooth or finished

surface, due to the short, fine fibers 5. They are also excellent thermo non-conductors and are therefore especially adapted for use as heat insulating walls or linings for 60 buildings.

When so employed they may be painted directly, or may be coated with cement, plaster or stucco compositions, with which they bond readily notwithstanding their 65 smooth surface. Under certain circumstances, however, it may become desirable to increase the bonding properties, and to this end I propose to indent or slot the surface of the said boards in the manner which will 70 now be more fully explained.

Owing to the high degree of porosity of the boards, and further, owing to the several different kinds or classes of fibers used, as above pointed out, it has been found impractical to produce a clean indentation or slot in the said boards by the use of the ordinary methods and apparatus. Attempts along this line have resulted in exceedingly 75 ragged holes, or in holes wherein the long thread- and hair-like fibers were bent and matted down so as to substantially close the pores of the board. It is of course desirable that these said pores be left open as much as possible so that the coating composition 80 such as plaster, stucco, etc., may enter therein and bond therewith.

I have found, on the other hand, that by employing a cutter such as that illustrated in Figures 1, 3 and 4, revolving at a high 90 rate of speed, a relatively clean slot or indentation may be produced in which the pores are not clogged, as above disclosed, but are left open and in condition to permit the ready entry of the plaster or other composition therein, thus providing better bonding than would otherwise be the case.

The said cutter 6 is preferably shaped substantially as shown, and is provided with a plurality of sets of cutting teeth 7 and 8. 100 The teeth 7 are approximately V-shaped in cross section, as shown in Fig. 4, providing the cutting points or apexes 9 and 10. These said points are adapted to make simultaneous incisions at opposite sides of the slot or indentation 11, leaving a substantially pyramidal portion 12 therein, as indicated by the dotted lines in Fig. 1. This said portion 12 however, is removed by the teeth 8, the cutting portion of which is substantially 110 straight, as shown in Fig. 4.

The teeth 8, as shown in Fig. 3, alternate

around the periphery of the cutter 6 with the teeth 7, so that as soon as the twin incisions are made by the points 9 and 10 of a tooth 7, the pyramidal portion 12 which is 5 left is cut out by the following tooth 8, as will be readily apparent. As above stated, slots or indentations made in this manner are found to be relatively clean cut, the pores of the board being left clear and in condition 10 to receive the plastic material, such as 14, Fig. 5.

The cutter 6 may be secured to a revolving spindle 15 in any suitable manner, as by the screw 16, and the said spindle may be driven 15 from any suitable source of power, not shown.

It is obvious that the indentations 11 may be made of any desired size, and at any angle to the surface of the board 1, but I 20 prefer to make them substantially as shown, so that when the board is in position upon the wall, and the plastic composition 14 is applied thereto, downwardly projecting lugs

17 will be formed, as shown in Fig. 5. This will further increase the efficiency of the construction, as will be readily apparent. 25

What I claim is:—

1. The herein described new article of manufacture comprising a board composed of a plurality of classes of felted cellulose fibers and provided with clean cut indentations, substantially as described. 30

2. The herein described new article of manufacture comprising a heat insulating plaster board composed of a plurality of 25 classes of felted cellulose fibers, and provided with a plurality of clean cut plaster bonding indentations cut in one of its surfaces, substantially as described.

In testimony whereof I affix my signature. 40
in presence of two witnesses.

CARL G. MUENCH.
